Horace Barnes, Attorney

UNITED STATES PATENT OFFICE.

HARRY B. JOHNSTON, OF SEATTLE, WASHINGTON.

PISTON AND PISTON RING.

1,424,200.

Specification of Letters Patent. Patented Aug. 1, 1922.

Application filed December 5, 1919. Serial No. 342,823.

To all whom it may concern:

Be it known that I, HARRY B. JOHNSTON, a citizen of the United States of America, residing at Seattle, in the county of King and State of Washington, have invented certain new and useful Improvements in Pistons and Piston Rings, of which the following is a specification.

- This invention relates to improvements in pistons and piston rings, and has for its object the provision of a piston in which the pressure generated within the cylinder chamber acts directly upon the piston ring or rings which in turn causes a reaction upon an inclined wall to maintain a close sealing contact with the walls of the cylinder to retain the maximum working pressure of the steam, explosion, gas mixture or other power agent.
- 10 The invention consists in the novel construction of a piston, the ring-grooves therein, and packing-rings fitted to said grooves arranged and adapted to receive the direct expansion or impulsive forces within the power cylinder and in combination with inclined opposing surfaces upon the ring-grooves and rings, respectively, whereby said force tends to expand said ring, to force the same against the cylinder wall.
- 20 In the accompanying drawings,
- 25 Figure 1 is a view partly in vertical section and partly in elevation, of a power cylinder, piston and rings therefor, embodying my invention,
- 30 Figure 2 is a top plan view of one of the piston packing-rings of my invention partly broken away,
- 35 Figure 3 is a view in elevation, partly in section of one of said rings, on line III—III of Fig. 2.

40 Referring to said views, the reference numeral 1 designates the side walls, 2 the top wall of an internal combustion engine cylinder and 3 the power chamber therein. 45 5 indicates a piston reciprocally operative in said cylinder formed with a groove in its upper portion communicating immediately with said chamber. The top or dome of said piston may be formed with a plain 50 surface 6, as shown.

Said groove comprises a substantially vertical wall 7 at the tip thereof extending downwardly from said piston-top 6 for sufficient distance to afford space for considerable material in the upper portion of the contained packing-ring; thence a wall 8

inclined outwardly and downwardly is provided forming the upper wall of an annular projection 10 which terminates at its outer edge in a vertical wall 11. An inversely 60 directed inclined wall 12 of substantially the same degree of inclination as said wall 8 forms the lower surface of said projection which intersects with a substantially vertical wall 13 of a lower channel 15 of less recession or depth than the wall 7 and terminates at its lowermost extremity in an outwardly and downwardly directed wall 16 of approximately the same degree of inclination as said wall 8. 65 70

A packing-ring 17 is arranged and adapted to be operatively secured in said groove and consists in an upper horizontal face 18 normally in substantially the same plane as the top surface 6 of the piston, a vertical 75 face 19 opposing the vertical wall 7 of the groove, an inclined face 20 opposing and corresponding to the wall 8, a vertical face 21 arranged opposite to the wall 11, an inwardly and downwardly inclined face 22 80 opposing wall 12 of the groove, vertical face 23 arranged opposite the bottom wall 13 of the channel 15, and an inclined face 24 of approximately corresponding inclination to said wall 16 of the groove. A vertical outer face 25 is arranged and adapted to bear upon the wall 1 of the cylinder. 85

The ring 17 is preferably cut, as at 26, on a diagonal line as viewed in end elevation, or in any suitable manner. As designed 90 and assembled, clearance spaces are provided, between faces 19, 21, 23, and 25 of the ring and the respective opposing walls of the groove to afford opportunity for unavoidable deposit of carbon and to admit of 95 the limited movement contemplated in the operative functions of the ring.

In operation, the explosive charge of gas within the chamber 3 acts directly upon the top of the piston and partially upon the top 100 face 18 of the ring which causes the ring to bear and react upon the inclined wall 8 urging the ring outwardly and expansively upon the cylinder wall 1 and the passage of the power-fluid is sealed thereby from 105 escape about the piston by contact between the face 25 of the piston and the wall 1 of the cylinder and by the union between the wall 8 of the groove and the face 20 of the ring. 110

In the opposite or upward stroke of the piston when the compression below the pis-

ton may cause the leakage of cylinder oil past the piston and into the combustion chamber, the reaction forces between the inversely inclined wall 12 and the face 22 5 will prevent the passage of oil thereby and tend to maintain the slidale contact of the outer face 25 and the cylinder wall.

The invention is simple in construction, and is positive and uniform in its operation, 10 and the rings are extraordinarily durable in use as while receiving a portion of the direct power of the explosion or expansion gases, they are designed of somewhat larger dimensions and are not subject to the recurrent 15 expansion and contraction of the common type of ring but as they are substantialy maintained in operative contact with the cylinder wall by positive pressure, they are relieved from many of the effects due to 20 rapid alternations of tension.

What is claimed as new is:

1. In combination, a piston having a ring groove formed at the intersection of the upper surface and side wall of the piston, an 25 inclined wall in said groove extending outwardly and away from the working face of the piston, a ring mounted in the groove and having an inclined face corresponding to the inclined wall of the piston groove, coacting 30 means between the walls of the groove and ring to hold the ring in the groove, said ring having an outer face exposed to the working pressure of the cylinder and lying wholly substantially in a plane and extending from 35 the edge of the groove to the wall of the cylinder whereby the action of the pressure on the whole outer surface of the ring will exert a force substantially parallel to the line of travel of the piston.

40 2. The combination of a power cylinder, of a piston having a ring-groove formed at the intersection of the upper surface and side wall of the piston, an annular projection in said groove having oppositely in- 45 clined walls on its upper and under sides, and a piston ring mounted in said groove having its upper face forming a portion of the upper working surface of the piston, and formed with inclined faces opposing, 50 respectively, the said inclined walls of the groove.

3. In combination a piston having a portion cut away at the junction of the working face and the cylindrical wall thereof, an 55 annular rib extending from the face of said cut away portion between the edges thereof and having an inclined wall, a piston ring having a groove to receive the annular rib, the groove having an inclined face which 60 cooperates with the inclined wall of the groove to expand the ring when pressure is applied to the top of the ring.

4. In combination, a piston having a portion cut away at the junction of the working 65 surface and the side wall thereof, a pis-

ton ring for said cut away portion having an annular surface adjacent the working surface of the piston and forming a substantial continuation thereof and interlocking means between the piston and ring including an inclined surface on the piston and a similar surface on the ring cooperating therewith, the surfaces being in contact at a point substantially in line with the middle of the annular upper surface of the ring. 70

5. In combination, a piston having a portion cut away at the junction of the working face and the side wall thereof, a piston ring for said cut away portion, interlocking means between the piston and ring including an inclined surface on the piston and a co-operating inclined surface on the ring, the cooperating surfaces being in contact at a point substantially opposite the middle of the cylindrical surface of the ring. 75

6. In combination, a piston having a portion cut away at the junction of the working surface and the side wall thereof, a piston ring for the cut away portion having an annular surface adjacent the working surface 90 of the piston within the periphery of the cylindrical wall thereof and interlocking means between the piston and ring including an inclined surface on the piston and a similar surface on the ring cooperating 95 therewith, the surfaces being in contact at a point substantially in line with the middle of the annular upper surface of the ring and substantially opposite the middle of the cylindrical surface thereof. 100

7. In combination, a piston having a portion cut away at the junction of the working surface and the side wall thereof, a piston ring for the cut away portion, and interlocking means between the piston and ring 105 whereby pressure at the end of the piston will expand the ring, said means comprising two oppositely inclined surfaces on the piston and two oppositely inclined and cooperating surfaces on the ring. 110

8. In combination, a piston having a portion cut away at the junction of the working surface and the side wall thereof to form a groove, the groove having two oppositely inclined surfaces, a ring in the groove for 115 cooperation therewith, the ring having two surfaces inclined similarly to the inclined surfaces of the cut away portion, the ring having a substantial surface exposed to the same pressure as the head of the piston. 120

9. A piston having a portion cut away at the junction of the working surface and side wall thereof to form a groove, the groove having two surfaces inclined outwardly and away from a portion of the groove and in opposite directions relative to a plane perpendicular to the axis of the piston. 125

In testimony whereof I affix my signature.

HARRY B. JOHNSTON.
